(57) **CLAIM**

The ornamental design for a weight for vibration motor, as shown and described.

DESCRIPTION

FIG. 1 is a top front perspective view of a weight for a vibration motor showing my new design;

FIG. 2 is a bottom rear perspective view thereof;

FIG. 3 is a front view thereof;

FIG. 4 is a rear view thereof;

FIG. 5 is a right side view thereof, a left side view being a mirror image of the right side view;

FIG. 6 is a top plan view thereof; and,

FIG. 7 is a bottom plan view thereof.
